United States Patent Office.

MARSHALL P. SMITH, OF BALTIMORE, MARYLAND.

Letters Patent No. 99,488, dated February 1, 1870.

DRIER.

The Schedule referred to in these Letters Patent and making part of the same.

To all whom it may concern:

Be it known that I, MARSHALL P. SMITH, of the city and county of Baltimore, and State of Maryland, have invented certain Improvements in Apparatus for Drying Lumber, Erricks, Vegetables, Fruit, and other substances, of which the following is a specification.

The first part of my invention relates to the form and construction of the ovens or chambers in which the articles to be dried are placed.

The second part of my invention relates to the employment of a blast of hot air, introduced under pressure, in place of the natural draught of a chimney, as has heretofore been the plan in driers of this particular kind.

The third part of my invention relates to the manner of exhausting the moisture thrown off by the drying-substances.

Figure 1 is a perspective view of an oven, embodying my invention.

Figure 2 is a plan of the same.

Figure 3 is a vertical longitudinal section through line *a b* of fig. 2.

Figure 4 is a vertical transverse section through line *c d* of fig. 3.

Figure 5 represents a perspective view of my device, with the fan-blower and furnace attached.

Similar letters refer to similar parts.

A A is a rectangular oven or chamber, constructed of brick or any suitable material. Studding, lathed and plastered inside and out, will answer every purpose, it being only required that it be as air-tight as it can be made.

The dimensions vary with the article to be dried and the quantity required. For lumber, I prefer it

eight (8) feet wide, six (6) feet high, and fifty (50) to eighty (80) feet long. At either end are doors B B.

Running longitudinally beneath the floor, is a clay or iron pipe, C C, having outlets D D opening into the chamber, provided with valves *d d*, for the regulation of the hot air.

This pipe leads to a furnace, Y, in which the air is heated, and thence to a fan or blowing-engine, X, which creates the blast. By means of this pipe and its outlet, the temperature of every part of the chamber is completely under control, and can be varied as required.

At one end of the chamber is another larger pipe, E, leading to the open air.

Through the centre of this pipe is a second much smaller pipe, e, about half an inch in diameter, leading to the boiler, the steam from which, blowing into and through the larger pipe, creates a vacuum, and causes all the moisture and vapor eliminated from the drying-substances to be rapidly exhausted from the chamber.

What I claim as my invention, and desire to secure by Letters Patent, is—

1. A drying-chamber or oven, constructed with pipes for the admission of hot air and for the removal of the vapor, in the manner and for the purposes substantially as described.

2. In combination with the subject-matter of the foregoing, the application of the fan-blower, in the manner and for the purposes shown.

MARSHALL P. SMITH.
